(57) **CLAIM**

The ornamental design for a plant light, as shown and described.

DESCRIPTION

FIG. 1 is a top-front perspective view of a plant light according to the present invention;

FIG. 2 is a bottom-rear perspective view thereof;

FIG. 3 is a front elevation view thereof;

FIG. 4 is a rear elevation view thereof;

FIG. 5 is a left side view thereof;

FIG. 6 is a right side view thereof;

FIG. 7 is a top plan view thereof;

FIG. 8 is a bottom plan view thereof;

FIG. 9 is a fragmentary cross-sectional view taken in the direction of 9-9 in FIG. 3;

FIG. 10 is a fragmentary cross-sectional view taken in the direction of 10-10 in FIG. 3;

FIG. 11 is an enlarged view of an area circumscribed in FIG. 1;

FIG. 12 is an enlarged view of an area circumscribed in FIG. 6;

FIG. 13 is an enlarged view of an area circumscribed in FIG. 9;

FIG. 14 is an enlarged view of an area circumscribed in FIG. 9; and,

FIG. 15 is an enlarged view of an area circumscribed in FIG. 10.

The broken lines in FIGS. 1, 2, 7, and 8 are for the purpose of illustrating the environmental structures that form no part of the claimed design. The broken lines in FIGS. 1, 6, and 9-15 depict boundaries of enlargements of a plant light that form no part of the claimed design. The dot-dash-dot broken lines in FIG. 3 depict the cross-sectional cut lines that form no part of the claimed design.

1 Claim, 13 Drawing Sheets
